UNITED STATES PATENT OFFICE.

HENRY BRADLEY, OF CAULFIELD, NEAR MELBOURNE, VICTORIA, AUSTRALIA.

MEANS FOR DISINFECTING SANITARY PANS AND THE LIKE.

1,421,348.

Specification of Letters Patent. Patented June 27, 1922.

Application filed January 31, 1922. Serial No. 533,050.

To all whom it may concern:

Be it known that HENRY BRADLEY, a citizen of the Commonwealth of Australia, and resident of Payne Street, Caulfield, near 5 Melbourne, in the State of Victoria, Commonwealth of Australia, has invented a certain new and useful Improved Means for Disinfecting Sanitary Pans and the like, of which the following is a specification.

10 This invention relates to improved means for disinfecting sanitary pans, commodes and the like, and has been devised in order to provide cheap, simple and effective mechanism, the objects of which are hereinafter 15 described.

The essential characteristics embodied in the invention are as follows:—

1. The use combined with a closet seat cover or lid of a disinfectant reservoir extending if desired the width of the seat about its pivot and means for delivering predetermined quantities of the fluid, such means being characterized in that the reservoir is constructed in two parts being preferably cylindrical and formed with sealed watertight ends having projections or pins which form the pivot points of the seat and consequently the disinfectant fluid reservoir.

2. The disinfectant fluid reservoir is provided with a substantially long feed tray and in communication with which is a retaining chamber for predetermined quantities of disinfecting fluid, the position of the parts being such that on the raising of the seat 35 cover, a predetermined quantity of disinfectant fluid is displaced over the tray into the retaining chamber which is provided with a delivery pipe adapted on the lowering of the closet cover to deliver such predetermined quantity of fluid into the pan.

3. The formation of the tray with a projecting flange along its upper edge, such flange at the ends inclining upwardly; thus at the ends of the tray an opening is provided between the divided compartments of the reservoir.

4. The provision at the ends and top of the tray of holes to allow the rear division of the reservoir to drain through into the 50 fluid displacement division in which the fluid is spread over the tray into the discharging receiver below or at the rear of said tray, thus allowing of the displacement and discharge of the whole of the fluid in the reservoir, the position and size of the said holes

preventing the quick return of the fluid to the rear compartment of the reservoir.

5. The provision of a closet frame providing a fly proof frame from which deleterious odours are discharged through a flue 60 pipe externally of the room in which the closet or commode is positioned.

In order that this invention be more readily understood it will now be described with reference to the accompanying drawings in 65 which:—

Figure 1 is a perspective view of the apparatus, applied to a portable closet or commode.

Figure 2 is a perspective view of the apparatus.

Figure 3 is an elevation of the apparatus when raised.

Figure 4 is a side elevation of the discharge pipe.

Figure 5 is a longitudinal section thereof.

Figure 6 is a vertical central section of the cylinder.

Figure 7 is a longitudinal section of the cylinder.

Figure 8 is a modification of the bracket upon which the cylinder may be mounted.

The preferred means for discharging predetermined quantities of disinfectant fluid into the closet or commode pan after each 85 use, consists of a cylinder 1 having detachable flanged and packed ends 2 so as to provide a water tight reservoir for the disinfectant fluid. These end caps 2 are centrally formed with outwardly projecting pins 3 which are 90 received by brackets 4 on a board 4^a at the rear of the closet seat frame so providing a pivot for the reservoir and consequently the seat cover or lid 5 to which it is attached by forwardly extending brackets 6.

The reservoir 1 is divided into two compartments by a tray 7 which extends vertically as shown in Fig. 6. The tray 7 carries at its rear upper portion a fluid-retaining chamber 8. The tray is formed with upturned flanges 9 and holes 10 and 10^a at its opposite ends. The holes 10 and 10^a permit the disinfectant fluid to drain from the rear into the front compartment of the reservoir and the flanges 9 direct the fluid, when the cover 5 is lifted, toward the opening 12 provided at the top of the tray, through which opening the fluid passes into the chamber 8.

Leading from the discharging and retaining chamber 8 is a pipe 13 that passes 110

through the reservoir and another connecting discharge pipe 14 externally of the reservoir connects at right angles with the pipe 13, stop screws 15 and 15^a being provided on both pipes near the joint for cleansing purposes. Along the discharge pipe 14 and near its discharge end is a small chamber 16 so constructed as to receive the discharged fluid from the discharge pipe 14 and this chamber 16 tapers outwardly with closed outer and inner ends 17 and 17^a, a hole being formed in the discharge pipe 14 near the inner end of this tapered chamber which at its outer or wider end on its underside is provided with a discharge orifice 19 so that the fluid will run into the empty chamber and discharge into the pan when the seat lid is lowered. The out-take discharge pipe 14 is sufficient in length and extends past the hole where it discharges into the delivery chamber 16 to allow of an air cushion by means of closing the end of the discharge pipe 14 to prevent the action of the air, on the lid 5 being raised, from throwing out a bubble or drop of fluid.

The reservoir is fitted to the brackets 6 connecting the seat lid 5 and through a portion of the brackets 6 from a high fluid level, are two air pipes 20 which lead from the reservoir so as to allow the out flow of air as the reservoir and lid are in movement and to facilitate the flow of the fluid, while at the top of the reservoir is a filling plug 21.

An essential characteristic is the position at the ends of the tray 7 of the two holes 10 and 10^a which allow of the flow from the one side of the tray to the other and also allows of the whole of the chamber to be cleaned out of disinfectant if so desired before recharging, and these holes are sufficiently small to prevent the return of the fluid from the tray to the rear portion of the reservoir on any movement of the seat lid or cover.

The closet to which the invention is adapted may be portable or fixed and of any suitable size.

In operation when the lid 5 is raised the reservoir is also partially turned on its pivot automatically and a predetermined quantity of fluid delivers from the tray 7 into the receiving chamber 8; when the seat lid or cover 5 is lowered after usage, the fluid in the receiving chamber 8 leads off by gravity into the delivery pipes 13 and 14 to the small discharging chamber 16, thence by gravity into the pan, the delivery pipe 14 and discharge chamber 15 being preferably positioned in the lid or cover 5 which at the discharge point is cut away at 24' to allow the fluid to run into the pan and the cycle is continued.

In the modification of the bracket as shown in Figure 8, it will be seen that, when

the pins 3 are inserted in the eye 23, the cylinder cannot be removed from the platform unless the above mentioned bracket is unscrewed or otherwise detached from the platform.

This modification will be particularly useful in railway stations or schools or in fact, anywhere where persons are liable to interfere with the apparatus to the detriment of its future operations.

In the illustration more particularly illustrated in Figure 1, the invention is applied to a closet seat or commode which is adapted to be placed in the room, the combination being provided with a vent to carry away any deleterious odours which may arise within the compartment.

The outer casing or compartment 24 is provided with a cover to form a seat 25, the inside of the compartment 24 being adapted to receive a pan 26 which is accommodated upon angle iron runners or guides 27 seated upon, and secured to, suitable bearers 28.

The space provided under the pan 26 is adapted to receive a sand tray 29 which is so placed to receive any overflow from the pan 26, and absorb same.

Doors 30 may be provided on the front of the compartment 24 in order to give free access to the pan 26 and sand tray 29.

A flue pipe 31 is provided, being placed conveniently so that all deleterious odours that may arise from the pan are carried away from the building in which the apparatus is installed.

The apparatus shown in Figure 1 is secured to the seat 25 by screws which pass through the board 4^a into the rear of the seat or cover 25. The pipe 14 leads into the seating portion 32, and the operation hereinbefore described takes place.

I desire it to be understood that various modifications and improvements may be embodied without departing from the spirit and scope of the functions above described.

What I claim as my invention and desire to secure by Letters Patent is:—

1. The combination with a commode, comprising a casing, a receptacle therein, and a seat cover for said casing, of means for hingedly connecting said seat cover to the seat of said commode, comprising a reservoir for disinfecting fluid attached to said seat cover and means pivotally connecting said reservoir to said seat, and means within said reservoir whereby a predetermined quantity of said fluid will be discharged into said receptacle each time the seat cover is raised and lowered.

2. A construction as set forth in claim 1 including a pipe extending from said reservoir through which said predetermined quantity of fluid is discharged into said receptacle, the free end of said pipe being closed and said pipe being provided with a

- discharge orifice located adjacent to but at a sufficient distance from said closed end to provide an air pocket between said orifice and closed end to prevent an air bubble or 5 drop of fluid from being thrown from said discharge pipe as the seat cover is raised.
3. A construction as set forth in claim 1 wherein the means within the reservoir comprises a tray dividing the reservoir into two 10 chambers and a retaining chamber into which said tray is adapted to discharge a quantity of fluid when the seat cover is raised and from which the said fluid is adapted to be discharged when the seat 15 cover is lowered.
4. A construction as set forth in claim 2
- in which the discharge pipe carries near its outer end a small chamber into which said discharge pipe discharges the fluid through said orifice and from which the fluid is discharged into said receptacle through a corresponding orifice.
5. A construction as set forth in class 1 wherein the seat cover is secured to said reservoir by means of brackets provided with 20 air tubes therein leading into said reservoir.

Signed at Melbourne, Victoria, Australia, this 22nd day of December, 1921.

HENRY BRADLEY.

In the presence of—

SIDNEY HENDLEY,
JEANNE BOUSTIERE.
